UNITED STATES PATENT OFFICE.

FREEMAN, R. WILLSON, JR., OF WORTHINGTON, OHIO, ASSIGNOR TO THE JEFFREY MANUFACTURING COMPANY, A CORPORATION OF OHIO.

SYSTEM OF MINE-TRACKAGE.

No. 900,903.

Specification of Letters Patent.

Patented Oct. 13, 1908.

Application filed February 3, 1908. Serial No. 414,097.

To all whom it may concern:

Be it known that I, FREEMAN R. WILLSON, Jr., a citizen of the United States, residing at Worthington, in the county of Franklin and State of Ohio, have invented certain new and useful Improvements in Systems of Mine-Trackage, of which the following is a specification, reference being had therein to the accompanying drawing.

10 My invention relates to a system of trackage for mines and has for its object to provide improved automatic means for returning to the rooms the empty coal cars after they leave the mine cage at the bottom of

15 the shaft.

Figure 1 is a plan view of a cage room with tracks arranged according to my invention. Fig. 2 is a side elevation of the same. Fig. 3 is a detail view in elevation of the left-hand end of the cage room.

In the drawings, 1 indicates the cage room, and 2 an entry leading to the rooms in which the coal is being cut. The loaded coal cars are brought by way of the tracks 3—3, in the 25 entry to the cage room where they are moved on to the track designated by the numeral 4, preparatory to being elevated to the surface of the mine. By a suitable arrangement of automatic levers and tripping devices when 30 the loaded car nearest to the mine shaft 5 is uncoupled and released by the cage operator, it moves, under the action of gravity, down track 4, which has a small grade preferably of about one per cent., bumping the empty 35 car standing upon the cage 6 off the cage and being itself caught in position upon the cage.

I have shown two mine shafts each provided with a cage, the track 4 having the branches 4'—4', each of which leads to one of 40 the shafts. The empty car upon leaving the mine cage moves along track 5', which is graded downwardly from the mine shaft until it reaches the point 5^a where it passes upon a section of track 7 oppositely graded 45 at a considerable angle to the horizontal. The car is carried up this incline by means of the car haul mechanism indicated as a whole by 8, and which may be of any desirable or suitable character.

50 For purposes of illustration, I have shown such an apparatus comprising the haulage chain 9 equipped with the lugs 10 for engaging corresponding lugs 11 on the bottom of

the cars, this chain passing around the idle sprocket wheel 12 at one end of its course and 55 at the other end of its course around the sprocket wheel 13, which is driven by the motor 15.

When the car has reached the top of this incline, it runs by gravity down the section 60 of track designated 16, to the switch-back 17. From the switch-back to the mine entry 2, the car descends along the return track 18, and is hauled by any suitable means to the 65 rooms to be reloaded. The switch-back 17 may be provided with a spring-operated 70 switch, or may be operated by a lever under the control of the cage-man. The distance vertically through which the empty car is elevated by means of the car haul is sufficient to provide a continuous down grade 75 from the top of the track section 7 to the switch-back and thence to the entry.

What I claim is:

1. A track system for a mine cage room, 75 comprising the loaded car track 4 extending from the room doorway to the mine shaft, and a return track extending from the opposite side of the mine shaft to the said doorway, said return track having a down-grade 80 section 5, an up-grade section 7, and thence a down-grade section to the room doorway, and a car haul mechanism for said up-grade section 7, substantially as set forth.

2. A track system for a mine cage room, 85 comprising the loaded car track 4 extending from the entry tracks to the mine shaft, an upwardly inclined track section 7, on the opposite side of the shaft, a car haul mechanism for moving the cars up said track section 90 7 and a return trackway extending from said track section 7 to the entry tracks, substantially as set forth.

3. A track system for a mine cage room, 95 comprising the loaded car track on one side of the shaft, the empty car track leading from the other side of the shaft, said empty car track comprising the section 5 graded downwardly from the shaft the oppositely inclined section 7, the down-grade 16, switch-back 17 and down-grade 18, and means for moving the cars up the inclined track section 100 7, substantially as set forth.

4. A track system for a mine cage room, 105 comprising the loaded car track on one side of the shaft, the empty car track leading

from the other side of the shaft, said empty car track comprising the section 5 graded downwardly from the shaft the oppositely inclined section 7, the down-grade 16, switch-
5 back 17 and down-grade 18, and the car haul mechanism 8 for the inclined track section 7, substantially as set forth.

In testimony whereof I affix my signature, in presence of two witnesses.
